UNITED STATES PATENT OFFICE.

ALBERT G. SCHERER, OF CHICAGO, ILLINOIS, ASSIGNOR TO THE EXCELSIOR STEEL FURNACE COMPANY, OF CHICAGO, ILLINOIS, A CORPORATION OF ILLINOIS.

STACK-HEAD OR BOOT FOR HOT-AIR STACKS.

1,155,761.

Specification of Letters Patent.

Patented Oct. 5, 1915.

Application filed July 16, 1915. Serial No. 40,167.

To all whom it may concern:

Be it known that I, ALBERT G. SCHERER, a citizen of the United States, and a resident of the city of Chicago, county of Cook, and 5 State of Illinois, have invented certain new and useful Improvements in Stack-Heads or Boots for Hot-Air Stacks, of which the following is a specification.

My invention relates to the construction 10 of hot-air stacks for use in connection with furnaces for heating houses and other buildings. It is well known that these stacks are frequently made of tin or sheet metal in a plurality of sections and assembled in the 15 walls of the building when being installed. Suitable lateral openings are made in the walls for the mounting of a register-frame or face. Frequently in placing the boot or 20 stack-head in position, difficulty is encountered in inserting the same through this opening in the wall. Heretofore the interlocking members on the boot have been so disposed that the total height of the boot was greater than the height of the opening 25 in the wall, so that the above difficulty was encountered. It is to obviate the objection that I have designed the improved construction in the hot-air boot herein disclosed.

It is therefore an object of my invention 30 to provide a boot that has its lock-portion adapted to engage and lock with an adjoining section disposed in a plane below or in the same horizontal plane with the upper edge of the register-frame and opening.

Another object of my invention is the 35 provision of a boot that is capable of easy assembly with other sections of a hot-air stack, of either double or single wall construction.

Still other objects are the provision of a 40 boot that is constructed so that the interlocking member may be disposed in the manner stated, without altering the dimensions of the register opening, and which at 45 the same time is comparatively inexpensive to manufacture and does not add to the cost thereof.

I prefer to accomplish the divers objects 50 of my invention by the means and in the manner hereinafter fully described and as more particularly pointed out in the accompanying drawings forming a part of this specification, wherein—

Figure 1 is a perspective view of a double

wall hot-air stack, showing my improved 55 boot in position and about to be assembled therewith. Fig. 2 is a side elevation of the upper portion of my improved boot. Fig. 3 is an exaggerated section thereof, showing the manner of assembly with the upper stack 60 or section.

Referring to the drawings, A and B designate the upper and lower sections, respectively, of a hot-air stack and C is my improved boot that is adapted to be interposed between the same and interlock therewith so that the register opening in the boot will coincide with the register opening in the wall. The front wall 5 of the boot is preferably open or has a portion thereof cut 65 away to provide a seat in which the register-frame is adapted to be mounted. The top or upper wall 6 extends a short distance to the rear of the front wall 5 and is then bent downwardly and inwardly at an abrupt 70 angle thereto, to provide an inclined wall 7. The side wall 8 of the boot C is preferably cut or shaped in a manner to correspond with and fit the contour of the top wall, and from the lower end of the inclined wall 75 7 to the opposite or rear wall, said side wall 8 is preferably terminated on a horizontal plane and is suitably shaped, as at 9, to receive the outer member of the double wall 80 upper section that may be mounted thereon. 85 The inner, or what may be termed the rear wall 10 of the boot, extends a slight distance above the portion 9, and is provided with interlocking rib 11, whereby the inner wall of 90 the upper section is secured or locked thereto. The upper edge of this inner wall terminates in a plane horizontally alining with or in a place below the portion 6 of the top wall of the boot, and, in the event 95 the boot is at the upper end of and terminates the stack, a suitable metal cap 12, having down-turned interlocking side flanges 13, may be placed over the same, as shown in Fig. 2 of the drawings.

From the above it will be observed the 100 upper or interlocking portion of the boot does not extend above the horizontal plane of the top wall of said boot, and when the boot is inserted through the register opening in the wall, there are no projections on the 105 same that interfere with the free insertion thereof. At the same time the dimensions of the register opening in the boot are not re-

duced, and by the employment of the inclined wall 7 a clear, free flow of hot-air from the stack is secured.

While I have herein illustrated and described certain specific means for carrying out my invention, it of course, will be obvious to others skilled in the art to which my invention pertains, that divers modifications and refinements thereof are possible 10 without materially departing from the spirit of my invention. I therefore desire it understood that all such changes are contemplated within the scope of my invention as expressed in the appended claims.

15 What I claim is:—

1. A double-wall hot-air stack consisting of a plurality of sections having connected inner and outer walls, said sections adapted to fit together end to end by both the inner 20 and outer walls, and a double wall section adapted to interlock respectively with an upper and a lower section and having its upper interlocking portion disposed in or below the plane of the top of the vertical 25 front walls thereof.

2. A boot for hot air stacks comprising a four walled structure, a portion of one of said walls being cut away to provide a register opening and means on the top of said boot whereby the same is adapted to be interlocked with a superimposed stack section, said means being disposed in a plane at or 30 below the horizontal plane of the upper edge of the cut away wall.

3. A register boot for hot-air stacks comprising a four-walled structure, a portion of one of the vertical walls thereof is cut away to provide a register opening, a top wall therefor consisting of a strip of metal bent 35 upon itself and having a portion intermediate its ends bent substantially V-shape and extended down inside said boot.

4. A register boot for hot-air stacks comprising a four-walled structure, a portion of 40 one of the vertical walls thereof being cut

away to provide a register opening, a top wall therefor consisting of a strip of metal bent upon itself and the folded edge whereof is bent at substantially right angles which constitutes the upper edge of the register 50 opening, the top being extended from said flange rearwardly and then downwardly and the layers of said top being then separated and formed into means for securing the interlocking of said boot with an adjacent 55 stack section.

5. A register boot for hot-air stacks comprising a four-walled structure, a portion of one of the vertical walls thereof being cut away to provide a register opening, a top 60 wall therefor consisting of a strip of metal bent upon itself and the forward portion thereof being horizontally disposed adjacent the front wall of the boot and its rear portion vertically disposed with its upper edge 65 terminating in a plane at or below the horizontal plane of the front portion of said top wall.

6. A register boot for hot-air stacks comprising a four-walled structure, a portion of one of the vertical walls thereof is cut away to provide a register opening, a top wall therefor consisting of a strip of metal bent upon itself and the forward portion thereof being horizontally disposed adjacent the 70 front wall of the boot and its rear portion vertically disposed with its upper edge terminating in a plane at or below the horizontal plane of the front portion of said top 75 wall, the intermediate portion of said top wall being inclined from the lower edge of said vertically disposed portion to said horizontally disposed portion.

Signed at Chicago, county of Cook and State of Illinois, this 14th day of July 1915. 80 85

ALBERT G. SCHERER.
